Michael G. Groff

United States Patent Office.

MICHAEL G. GROFF, OF VOGANNSVILLE, PENNSYLVANIA.

Letters Patent No. 80,164, dated July 21, 1868.

IMPROVED HORSE-POWER.

The Schedule referred to in these Letters Patent and making part of the same.

TO ALL WHOM IT MAY CONCERN:

Be it known that I, MICHAEL G. GROFF, of Vogansville, in the county of Lancaster, and State of Pennsylvania, have invented new and useful Improvements on a Combined Jack and Horse-Power; and I do hereby declare that the following is a full, clear, and exact description of the construction and operation of the same, reference being had to the accompanying drawings, making a part of this specification, in which—

Figure 1 is a perspective drawing of the jack and horse-power combined.

Figure 2, a plan view of the horse-power.

Figure 3, side elevation and portions enlarged.

Figure 4, the gear of the jack in part.

The nature of my invention consists in bringing the gearing in a horizontal line, and so arranged as to divide the friction, and consequent wear, counterpoise the pressure, and to increase the power and durability of the machine, together with a stationary platform and minor improvements.

To enable others skilled in the art to make and use my invention, I will proceed to describe its construction and operation.

The main or sweep-wheel A is in a horizontal position, say six feet in diameter, held in a square frame, K K K, at four points, by bracket-plates. These frame-pieces have one end extended, as shown. A cross-brace, k, may also be added, as shown by the dotted lines in fig. 1, as is common for connecting the draught of the horses, being simply levers for turning the main wheel A.

This wheel has centrally-raised cogs, slightly bevel on the upper and lower surface, leaving a plane flange on both the inner and outer circumference. This flange, on the inside, is embraced by a series of pulleys, D, having overlapping flanges, which answer for friction-pulleys, as well as to support the main wheel. Other friction-rollers, I J, fig. 3, may be employed, as in other instances.

The pulleys K are held in brackets attached to the four posts E, and also otherwise to the frame G G' H, to which the posts E are firmly fastened and stayed by cross-pieces or otherwise.

A shaft, B, having its bearings mounted in the front and rear cross-pieces G G', is provided with two pinions, C C, said shaft being slightly inclined, so that the one meshes into the cogs of the upper surface of the main wheel, and the other in those on its lower surface. This shaft is connected, by means of a universal joint, L F, to the shaft M, that drives the jack O, or outside gear and band-wheel N, fig. 1.

The jack O is also provided with cogs on each side, and flange around the circumference, to which the brackets or curved arms z are affixed, standing obliquely to the shaft T, so that the two pinions t mesh into the cogs on the opposite sides of the same.

The shaft T has its bearings in a bracket on the rear cross-piece q, and box or journal on the side-piece r. To this shaft the band-wheel N is affixed.

A circular or square stationary platform is supported on the posts E.

Fig. 1 shows a lever in a slot, for arresting the motion when stopping the machine to lock the shaft.

Other minor details are suggested, which form no part of my invention.

I am aware that, independently considered, the various parts forming the combination are not new, but the arrangement of these several parts constitutes this a horse-power differing substantially from any other of the machines of the like kind heretofore in use, and, as a whole, has a combination of features that makes it peculiarly valuable; and it is confidently believed that, by this arrangement, the wear is lessened, and the leverage of the circumference of the main and jack-wheel obtained at two points on the same shaft, in a manner to divide the ordinary pressure, while the horse, pulling on one lever-arm, also pushes, so that the same force applied to move the one pinion in pulling, exerts the same leverago on the other end of the shaft and pinion by pushing, and must necessarily greatly reduce the power, even if the friction be somewhat increased, as a fair trial of the machine has clearly proved.

What I claim as my invention, and desire to secure by Letters Patent, is—

The peculiar arrangement of the main wheel A and jack O, with the horizontal or inclined shafts T B, having each two pinions, the gear connected by the shaft M, which is provided with universal joints, substantially combined in the manner and for the purpose specified.

In combination with my arrangement in the gearing aforesaid, I also claim the stationary platform, supported substantially in the manner specified.

I also claim attaching the spokes or arms z on the outer circumference of a wheel, O, which wheel has cogs on both sides, when said spokes or arms are so curved as to admit the free action of a pinion, t, on each side of the face of said wheel, in the manner shown and for the purpose specified.

MICHAEL G. GROFF.
